UNITED STATES PATENT OFFICE.

JOHN ROSE, OF PHILADELPHIA, PENNSYLVANIA.

UMBRELLA-CASE.

1,108,240.

Specification of Letters Patent.

Patented Aug. 25, 1914.

Application filed December 9, 1913. Serial No. 805,524.

To all whom it may concern:

Be it known that I, JOHN ROSE, a citizen of the United States, residing at Philadelphia, in the county of Philadelphia and 5 State of Pennsylvania, have invented certain new and useful Improvements in Umbrella-Cases, of which the following is a specification.

This invention relates to umbrella cases.

10 The object which I have in view is to provide an umbrella case so formed that it will maintain a uniform, smooth appearance throughout when surrounding a rolled umbrella, and the shape whereof will not be 15 affected by the folds of the umbrella cover located within it, or by the contour of a rolled umbrella, which by reason of the shape of the cover is thinner at a point adjacent to the handle.

20 A further object is to provide an umbrella case having the characteristics above referred to which shall be capable of ready application to and removal from a rolled umbrella.

25 With these objects in view the invention consists of an umbrella case having the novel generic and specific features of formation an aggroupment of the parts substantially as hereinafter described and claimed.

30 The invention is illustrated in the accompanying drawing in which;

Figure 1 is a side view of a completed case applied to an umbrella; Fig. 2 is a view showing the outer and intermediate parts 35 of the case turned up to show their disposition; and, Fig. 3 is a sectional view of the ferrule of the case.

The body of the case employed is made up of three thicknesses of material. The outer 40 or face portion 1 may be of silk or other fabric, leather or other flexible material. The inner or lining portion 2 is preferably of some smooth material for instance satin or a similar fabric which will offer no resistance to the introduction and withdrawal 45 of a folded umbrella.

The materials forming the outer and inner faces respectively of the cover are joined in any suitable way, as for instance by interposing between them a layer 3 of adhesive substance which will remain flexible offering no difficulty in closely folding the case when removed from an umbrella, and at the same time giving sufficient stiffness 50 to the case to preserve its shape in all conditions when in use. Instead of joining the

inner and outer layers of the case as described they may be connected by a fabric coated on both sides with some adhesive substance, forming a lining, or such lining 60 may be attached by sewing or any other suitable way.

The smaller end of the case has attached thereto a ferrule 4 which receives the end of the case, and which has a closed lower 65 end designed to receive the end of an umbrella stick opposite to that at which the handle is attached. Removed a short distance from the open end of the ferrule 4 is an interior groove or socket 5 extending entirely around the ferrule. In attaching the end of the case to the ferrule a cylinder 6 of an interior diameter slightly less than the interior diameter of the open end of the ferrule, and having an exterior bead or projection 7, is placed in the interior of the small 70 end of the case and the two parts are forced into the end of the ferrule bringing the bead 7 into the groove or socket. When the parts are thus placed the permanent attachment of 75 the end of the case to the ferrule is effected without the necessity of other securing means.

The larger end of the case which when applied to a rolled umbrella is intended to 80 abut against the inner end of the handle of the umbrella, is of a size corresponding to the diameter of the handle end. Thus the handle, body of the case and ferrule present the appearance of a cane. The body of the 85 case, formed as described, preserves its symmetrical form unaffected by the thin body presented by the ends of the ribs of the umbrella adjacent to the handle.

The case formed as described is not distorted or contracted by forcing an umbrella into it as occurs when the case is formed in the usual way, generally by a material corresponding to that used for umbrella covers. As the interior of the case is smooth the introduction or withdrawal of a rolled umbrella may be easily effected even if the cover of the umbrella is wet. By reason of the construction of the case its outer appearance is not changed by the irregular shape 100 of the rolled umbrella introduced into it, but on the contrary its symmetrical form is preserved.

I claim.

1. An umbrella case comprising an outer 110 face portion of flexible material, a lining having a smooth inner face, and an inter-

posed layer connected to the face portion and the lining, whereby a flexible case capable of close folding and whose surface when applied to a rolled umbrella is unaffected by 5 the folds of the cover thereof, is provided.

2. An umbrella case comprising an outer face portion of flexible material, a lining having a smooth inner face, and an interposed adhesive layer.
- 10 3. A taper umbrella case comprising an outer portion of flexible material, a lining having a smooth inner face, an interposed connecting layer, and a hollow ferrule having a closed outer end connected to the 15 smaller end of the case, the ferrule being of a size and shape to form an unbroken surface throughout the case and ferrule.
4. The combination with an umbrella of

a taper case the larger end of which corresponds in size to the inner end of the handle of the umbrella, the body of the case being composed of an outer flexible face, a lining having a smooth inner face, and an interposed connecting layer, and a hollow ferrule having a closed end connected to the smaller end of the case, the ferrule being adapted to receive and inclose the tip end of the umbrella rod and being of an exterior size and shape to form an unbroken surface throughout the case and ferrule.

25 30 In testimony whereof I affix my signature in presence of two witnesses.

JOHN ROSE.
